COMBINED COVER AND FOOD MOLD INSERT

James B. Swett, Barrington, R.I., and Richard A. Boucher,
Northboro, Mass., assignors to Dart Industries Inc., Los
Angeles, Calif.

Filed Jan. 24, 1974, Ser. No. 436,325

Term of patent 14 years

Int. Cl. D7—02

U.S. Cl. D7—131

FIG. 1

FIG. 2

FIG. 3

FIG. 1 is an elevational view of a combined cover and food mold insert showing our new design;

FIG. 2 is a top plan view thereof; and

FIG. 3 is a bottom plan view thereof.

We claim:

The ornamental design for a combined cover and food mold insert, substantially as shown.
